Primary Examiner — Keith J Wilson(74) *Attorney, Agent, or Firm* — Crowell & Moring LLP(57) **CLAIM**

The ornamental design for a filter element, as shown and described.

DESCRIPTION

FIG. 1 is a front, right, top perspective view of a filter element showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the filter element in a state of use with broken line environment.

The dashed broken lines in FIGS. 6 and 7 depict portions of a filter element that form no part of the claimed design. The dashed broken lines in FIG. 8 are for illustrating environment structure only and form no part of the claimed design.
